CAB AND BODY STRUCTURE FOR AN EXCAVATOR

Ellis A. Sitton, East Peoria, Glenn W. Shields, Sandwich,
William O. Smart, Dunlap, and Cleon C. Streitmatter,
Aurora, Ill., assignors to Caterpillar Tractor Co., Peoria,
Ill.

Filed Aug. 25, 1972, Ser. No. 283,833

Term of patent 14 years

Int. Cl. D12—09

U.S. Cl. D14—27 B

FIG. 1 is an isometric view taken from above and to the left front of the cab and body structure for an excavator embodying our new design; and

FIG. 2 is an isometric view taken from above and to the right rear of the cab and body structure for an excavator embodying our new design.

We claim:

The ornamental design for a cab and body structure for an excavator, substantially as shown.
